United States Patent Office.

JOHN S. ARMSTRONG, OF PRAIRIE DU CHIEN, WISCONSIN.

Design No. 2,595, dated March 12, 1867.

DESIGN FOR A MILITARY MONUMENT.

The Schedule referred to in these Letters Patent and making part of the same.

TO ALL WHOM IT MAY CONCERN:

Be it known that I, JOHN S. ARMSTRONG, of Prairie du Chien, in the county of Crawford, in the State of Wisconsin, have produced a new Design for Soldiers' Cenotaph, Military, County, and State Monuments; and I do hereby declare that the following is a full and exact description thereof, reference being had to the accompanying drawing, and to the letters of reference marked thereon.

The design consists in a main monument in any of the usual and known forms, as shown by the letter *a* in the accompanying drawing, with one prominent or eagle block made of marble, as shown by the letter *b*, into which block is cut or sculptured, at each corner thereof, an eagle, as shown at *c*, surmounted with the statue or figure of a man in military dress, in the position shown at *d*, combined with eight small pedestals or monuments erected or placed around the main monument, as shown at *e*, the pedestals to be made of marble, and each surmounted by a cannon.

What I claim as my invention, and desire to secure by Letters Patent, is—

A design for a monument, as shown and described.

JOHN S. ARMSTRONG.
